UNITED STATES PATENT OFFICE.

ALEXIS L. LAMAR, OF PITTSBURG, KANSAS, ASSIGNOR, BY DIRECT AND MESNE ASSIGNMENTS, OF SIX THIRTY-SECONDS TO JOSEPH R. HINKLE, SEVEN THIRTY-SECONDS TO O. L. STAMM, TWO THIRTY-SECONDS TO GEO. H. STUESSI, ONE THIRTY-SECOND TO H. DEGEN, SR., FOUR THIRTY-SECONDS TO JOSEPH M. BOURNONVILLE, AND EIGHT THIRTY-SECONDS TO SAMUEL JOHN POLE, ALL OF PITTSBURG, KANSAS; ONE-SIXTEENTH TO JAMES JEPSEN AND PETER FISCHER, AND ONE-SIXTEENTH TO P. T. ELLIS.

KEROSENE-VAPORIZER FOR INTERNAL-COMBUSTION ENGINES.

1,296,972.

Specification of Letters Patent. Patented Mar. 11, 1919.

Application filed April 21, 1916. Serial No. 92,766.

To all whom it may concern:

Be it known that I, ALEXIS L. LAMAR, a citizen of the United States, residing at Pittsburg, in the county of Crawford and 5 State of Kansas, have invented certain new and useful Improvements in Kerosene-Vaporizers for Internal-Combustion Engines; and I do hereby declare the following to be a full, clear, and exact description 10 of the invention, such as will enable others skilled in the art to which it appertains to make and use the same.

This invention relates to a kerosene vaporizer for internal combustion engines, 15 and has for one of its objects the provision of a device whereby the kerosene is efficiently vaporized within the intake manifold and pipe by the exhaust gases of the engine within the exhaust manifold and 20 pipe which completely surrounds the intake manifold and pipe.

Another object is the provision of means for introducing gasoline into the intake pipe of the manifold to provide for the 25 initial starting of the engine.

A further object is the provision of means for injecting a stream of water into the intake manifold to be converted into steam for commingling with the kerosene 30 vapor formed in the intake manifold during the employment of the kerosene mixture.

A further object is the provision of a vaporizing device constructed in a manner 35 for causing an equal distribution of the exhaust and the utilization of the maximum amount of heat contained therein.

A still further object is the provision of 40 novel means for attaching the device to an engine.

And a still further object is the provision of a kerosene vaporizer which can be readily attached to any of the well known make of engines without the necessity of 45 making alterations in the engine construction, and which is simple in construction, efficient in operation, and which can be manufactured and sold upon the market at a nominal cost.

50 These and other objects and advantages will more fully appear as the nature of the

invention is more clearly understood from the following specification, the subject matter of the claims, and the views illustrated in the accompanying drawings, in which:

Figure 1 is a vertical sectional view through the device, showing the detail construction thereof.

Fig. 2 is a perspective view showing the invention in applied operative position 60 upon an engine, the engine being shown as partly broken away.

Fig. 3 is a fragmentary detail sectional view on line 3—3 of Fig. 2.

Fig. 4 is a view in elevation of one of 65 the yokes employed in attaching the device to the engine.

Fig. 5 is a view in elevation of one of the T-bolts used in connection with the yoke of Fig. 4 for attaching the device to an 70 engine.

Referring to the drawings wherein similar reference characters denote corresponding parts throughout the several views, 1 denotes the upper portion of the cylinders 75 of an engine, 2 the exhaust manifold, and 3 the exhaust pipe leading centrally therefrom.

The exhaust manifold 2 consists preferably of an elongated cylinder provided with 80 rounded ends and its exhaust pipe 3 extending from its lower side at a point midway between its ends and disposed obliquely therefrom for a portion of its distance. At one side of the exhaust manifold 2 are formed the ported exhaust nipples 4 adapted to be seated in the ends of the exhaust ports of the engine.

Within the exhaust manifold 2 is the intake manifold 5 provided at one of its sides 90 with the intake nipples 6 which project through the side of the exhaust manifold 2 and are adapted to be seated within the intake ports of the engine. The intake manifold 5 is also preferably formed of an elongated cylindrical construction provided with rounded ends, and is of less length and less diameter than the exhaust manifold 2 to provide ample space therebetween, and extending from the under side of the intake 95 manifold 5 and from a point substantially midway between its ends is the intake pipe 100

7 which is also disposed in oblique direction from the intake manifold 5 for a portion of its distance and within and in spaced relation to the exhaust pipe 3, the lower portion of the intake pipe 7 being curved laterally in acute angular relation to provide the attaching end 8 which projects through and beyond one of the side walls of the exhaust pipe 3. Within the end 8 of the intake pipe 10 7 is the butterfly valve 9 operated through any suitable means. Suitably secured to the attaching end 8 of the intake pipe 7 is any suitable form of kerosene carbureter 10 supplied with oil by the pipe 11. Secured to 15 the carbureter 10 is the hot air pipe 12, provided with the butterfly valve 13 operated by any suitable means. The hot air pipe 12 extends upwardly to the hot air casing 14 which is concavo-convex in cross section 20 and has its opposite side edges resting against the under side of the exhaust manifold 2 for supplying hot air to the carbureter 10.

As shown, the open end of the hot air casing 25 is disposed innermost and adjacent the juncture of the exhaust pipe 3 with the exhaust manifold so that the heat radiated from them and the surrounding warm air may be drawn directly into the hot air casing 30 and again superheated in its passage along beneath the exhaust manifold just prior to its entrance into the kerosene carbureter.

The intake manifold 5 and its intake pipe 35 7 are supported in spaced relation to and within the exhaust manifold 2 and its exhaust pipe 3 through the medium of the intake nipples 6 which project from one side of the intake manifold 5 and open through 40 one side wall of the exhaust manifold 2. The nipples 6 thus connect the intake manifold 5 with the exhaust manifold 2, and at the opposite side of the intake manifold 5 there is a fillet or neck 15 which connects 45 this wall of the intake manifold 5 with the adjacent wall of the exhaust manifold 2. Also extending from the outer wall of the intake pipe 7 at any suitable point is another fillet or neck similar to the fillet or neck 15 for securing this side of the intake pipe 7 to the adjacent wall of the exhaust pipe 3. The intake manifold 5 and its intake pipe 7 are also additionally reinforced and supported by the attaching end 8 of the 50 intake pipe 7 being rigid with and opening through one of the walls of the exhaust pipe 3. The parts 2, 3, 5, 7, 8, 15, 4 and 6 are preferably cast in an integral structure, but these parts may be made separately and 55 secured together.

For injecting a stream of water into the intake manifold 5 to be converted into steam for commingling with the vaporized kerosene and hot air, the upper fillet or neck 15 60 has the port 16 formed therethrough and

screw threaded in the outer end of the neck 15 is the tube 17 of the valve casing 18 provided with any suitable form of valve 19 actuated by the valve stem 20 which extends to the dash board of the automobile or other suitable point, and connected to the valve casing 18 is the water pipe or hose 21 leading from any suitable source of water supply.

For supplying gasoline to the intake pipe 7 of the intake manifold 5 the lower fillet or neck similar to the neck 15 has also formed therethrough a port similar to the port 16 of the neck 15 and screw threaded in the outer end of this fillet or neck is the tube 22 of the valve casing 23 also provided with a valve similar to the valve 19 and actuated by the valve stem 24 which also extends to the dash board of the automobile or other convenient point, and for supplying 85 gasoline to the valve casing 23 the pipe or hose 25 is provided which leads to any suitable source of gasoline supply.

For securing the device upon an engine the yokes or U-shaped bolts 26 provided with the threaded ends 27 and the nuts 28 thereon are employed. These yokes 26 extend around and embrace substantially half of the circumference of the exhaust manifold 2 and have their threaded ends 27 secured in the apertures 29 formed in the ends of the heads 30 upon the stems 31 of the T-bolts, the stems 31 of these bolts being designed to pass through bores formed between the cylinders of the engine and secured 90 thereon by the nuts 32 which engage the threaded ends 33 of the T-shaped bolts at the opposite side of the engine. This means of attaching the device upon the engine firmly secures the same thereon with the exhaust nipples 4 of the exhaust manifold 2 securely seated in the ends of the exhaust ports of the engine and the intake nipples 6 firmly seated in the ends of the inlet ports of the engine, which connections may be 95 efficiently sealed with any suitable form of gaskets or the like, the attaching end 8 of the intake pipe 7 being connected to the kerosene carbureter 10 in any suitable manner as at 34 and the exhaust pipe 3 having 100 its end 35 connected in any suitable manner with the exhaust conducting pipe.

The operation of the device is briefly described as follows:

To start the engine the valve stem 24 120 is manipulated for actuating the valve in the valve casing 23 so that the gasoline will be drawn through the pipe 25 and into the intake pipe 7 and therethrough into the intake manifold 5 and into the respective 125 cylinders of the engine by the suction created therein and air may be admitted to the gasoline from the air pipe 12 by the proper manipulation of the butterfly valves 9 and 13 if desired. The engine will now run 130

- by the gasoline supplied thereto until the exhaust manifold 2 and its pipe 3 and the intake manifold 5 and its intake pipe 7 become heated by the exhaust gases of the engine whereupon the kerosene carbureter 10 will be so operated that the kerosene will also be drawn into the intake pipe 7 and the intake manifold 5 thereby commingling with the gasolene and at the same time the 10 valve stem 20 is manipulated for actuating the valve 19 in the valve casing 18 so that water is drawn through the pipe 21 through the port 16 in the upper neck 15 in a fine stream and by the heat of the exhaust gases 15 which have heated the surrounding walls of the exhaust manifold 2, the intake manifold 5 and the fillet or neck 15 is readily converted into steam and commingles with the vaporized kerosene and gasolene, the 20 gasolene, however, being gradually cut off by manipulating the valve stem 24 in the opposite direction until the gasolene is entirely cut off and the engine now runs efficiently upon the kerosene mixture, the kerosene 25 having been thoroughly vaporized by the air heated in the casing 14 which passes through the hot air pipe 12 into the carbureter 10, the steam increasing the efficiency of the mixture.
- 30 Having described my invention, what I claim as new and desire to secure by Letters Patent, is:—
1. In an internal combustion engine, the combination with an exhaust manifold having a depending exhaust pipe upon its lower side and middle portion, of an intake pipe, a 35 part of which is wholly within said exhaust pipe, while the remaining part of said intake
- pipe has on its receiving end a lateral extension fitted to the under side of the exhaust manifold and provided with a receiving opening immediately adjacent the exhaust pipe of said manifold, whereby initially heated air from the exhaust pipe will enter said intake. 40
2. In an internal combustion engine, the combination with an exhaust manifold having a discharge pipe and also having an intake manifold positioned within the exhaust manifold, of an integral hollow neck 50 connecting said manifolds, a liquid supply pipe connected to the outer end of said neck, and a valve to regulate the supply of liquid to said neck. 45
3. The combination with an exhaust 55 manifold operatively connected to the exhaust ports of the engine and having a depending exhaust pipe on its lower central portion, of an intake pipe operatively connected with the intake ports of the engine 60 and disposed partly within said exhaust pipe and manifold, said intake pipe having its exterior portion or receiving end shaped to fit the under side of the exhaust manifold and extended inwardly to a point adjacent 65 the point of union of said exhaust pipe with said exhaust manifold, whereby the only opening in the intake pipe will be immediately against said exhaust pipe.

In testimony whereof I have signed my name to this specification in the presence of two subscribing witnesses.

ALEXIS L. LAMAR.
